WILLET E. STARK, OF EAST CLEVELAND, OHIO, ASSIGNOR TO THE BRYANT HEATER & MANUFACTURING COMPANY, OF CLEVELAND, OHIO, A CORPORATION OF OHIO.

FLUE CONSTRUCTION

Application filed September 24, 1928. Serial No. 309,200.

This invention relates to boilers or water heaters particularly adapted for use in connection with the heating system of a building or the like, and more particularly has to do with a new and improved flue construction.

In the ordinary type of gas heater or gas boiler provision is made by means of a draft hood for the passage of the products of combustion from the interior of the boiler to the chimney. The draft hood ordinarily being of rather large construction and being disposed on the top of the boiler thereby takes up considerable head room.

It is, therefore, one of the improved features of the present invention to provide a flue construction, to take the place of the draft hood referred to, which is embodied in the construction of the boiler itself being disposed within the outer casing so as not to be visible from the outside thereby materially improving the appearance of the gas boiler.

A further object of the invention is to provide a flue construction embodying the invention which is inexpensive to manufacture, neat in appearance, and exceptionally efficient in operation.

With the objects above indicated and other objects hereinafter explained in view, the invention consists in the construction and combination of elements hereinafter described and claimed.

Referring to the drawing:

Figure 1 is a fragmentary vertical sectional view of the upper portion of a boiler or water heater embodying the present invention.

Fig. 2 is a top plan view of the boiler illustrated in Fig. 1 but with the cover plate removed to more clearly show the invention.

Fig. 3 is a perspective view of the baffle employed in the flue construction embodying the present invention.

In the drawing I have illustrated the upper portion of a gas boiler or water heater of the usual construction, embodying side walls 10, a front wall 11, and a rear wall 12, comprising a heat insulated casing for the boiler. A plurality of cast iron water sections 13, four of which are here shown, are arranged side by side and supported on a suitable base not

shown. These water sections 13 are suitably connected together at the top by an outlet manifold 14 while the lower portions of the water sections and at the rear are connected together in the usual manner by an inlet manifold not shown. Directly beneath the water sections 13 and not here shown, are gas burners adapted to heat the water sections. The products of combustion from the gas burners pass upwardly between the adjacent sides of the sections 13 and ordinarily pass off through the draft hood mounted upon the top of the boiler which communicates with the chimney. The draft hood is usually constructed so as to admit air from the boiler room to thereby break the intensity of the draft produced by the chimney and also for the purpose of diverting back drafts. This construction, however, requires considerable overhead room and does not present a very pleasing appearance.

It is the purpose of the present invention to provide a flue construction which is contained within the boiler casing to thereby materially improve the appearance of the gas boiler and at the same time eliminate the necessity for any appreciable amount of head room in connection with the installation of the boiler.

A cast iron flue top 15 extends substantially horizontally above the water sections 13 and has one end turned downwardly to provide a flange 16 which is supported upon the top of the water sections 13 as indicated at 17. The opposite end of the flue top 15 is provided with a depending flange 18 which has bolted or otherwise secured thereto a plurality of supporting arms 19, the lower ends of which rest upon the upper surfaces of the water sections 13 to thereby support the flue top 15 in proper position within the casing.

The flue top 15 is provided with a flanged opening 20 one of which is herein shown, one opening being sufficient for a gas boiler made up of four water sections 13. It should be understood, however, that where the number of water sections 13 are increased, depending upon the desired capacity of the boiler, the number of openings is also in-

creased as desired. This flanged opening 20 is adapted to communicate with the chimney by suitable pipes not shown, to thereby carry off the products of combustion from within the boiler.

5 Directly beneath the forward portion of the flanged opening 20 is a depending baffle 21 provided with an annularly extending flange 22, the upper surface of which is adapted to engage with the under surface of the flue top 15 adjacent the forward portion of the flanged opening 20. This baffle 21 is provided with laterally extending ears or 10 projections 23 integral with the outer surface of the flange 22 and the ears 23 are bolted or otherwise secured as at 24 to the flue top 15. The baffle 21 extends downwardly and rearwardly covering a portion of the flanged opening 20 and extends rearwardly 15 far enough to prevent the back drafts from passing from the chimney into the combustion chamber of the boiler.

As previously stated, the sections 13 are connected together and provided upon their 20 upper surfaces with abutting transversely extending lateral flanges 13a. These flanges 13a converge toward the center of the boiler and terminate short thereof to provide openings 13b. These flanges 13a tend to direct 25 or divert the products of combustion in their upward travel toward the openings 13b through which they pass to the chimney.

It is to be noted that the rearward edge 30 of the baffle 21 also extends slightly beyond the forward edge of the rear flanges 13a and as a result the back drafts coming down the forward portion of the chimney engage the baffle and are diverted somewhat laterally through the opening 27. The back drafts which pass downwardly at the rear portion 35 of the chimney through the flanged opening 20 engage the upper surface of the rear flanges 13a and are similarly diverted and pass through the opening 27 in the rear of the housing. It will, therefore, be readily 40 seen that the arrangement of these parts cooperates to prevent any back drafts from passing through the openings 13b into the combustion chamber.

45 The housing is provided with the usual insulated cover plate 25 and has a transverse opening 26 concentrically located with respect to the flanged opening 20 and of slightly larger diameter. The rear wall 12 is also provided with a transverse opening 27 adjacent the opening 26 in the cover plate 25 and is in communication with the boiler room or the surrounding atmosphere to thereby 50 admit air under normal conditions for the purpose of breaking the intensity of the draft produced by the chimney.

55 It will be noted that this flue construction incorporates the essential functions of the ordinary draft hood, namely, to admit air into the chimney from the boiler room to

break the intensity of the draft produced by the chimney, and also to provide a baffle for the purpose of diverting back drafts away from the combustion chamber. The products of combustion passing upwardly between the water sections 13 are drawn past the lower end of the baffle 21 and up through the flanged opening 20 due to the draft produced by the chimney. At the same time air is drawn in through the opening 27 in the rear wall 12 and thereby tends to break the intensity of the draft produced by the chimney. At the same time any back drafts within the chimney engage with the baffle 21 and are diverted causing them to pass outwardly through the opening 27 in the rear wall 12 and into the surrounding atmosphere thereby preventing them from entering the combustion chamber. It is therefore noted that the products of combustion in passing upwardly between the water sections 13 are compelled to change their direction of flow in passing into the chimney from a vertical direction to a horizontal direction.

60 While I have described the preferred embodiment of the invention it is to be understood that I am not to be limited thereto as changes and modifications may be made without departing from the spirit of the invention as defined in the appended claims.

Having thus described my invention, what I claim is:

1. A flue for sectional boilers and the like comprising a member adapted to be supported above the boiler sections and extending substantially entirely over the flue gas exit area between said sections; an opening in said member adapted to communicate with a chimney, a baffle disposed below a portion only of said opening whereby the back drafts from the chimney are diverted away from the combustion chamber of the boiler, and an enclosing member having an opening in one wall through which back drafts are adapted to pass to atmosphere. 110

2. In combination with a boiler having water sections and a housing enclosing the same, a flue disposed within said housing comprising a member supported by said sections, an opening in said member adapted to communicate with a chimney, a back draft deflector disposed beneath a portion of said opening, and means for admitting air into the boiler adjacent said opening whereby the intensity of the draft produced by the chimney is reduced. 115

3. A boiler of the character described comprising a plurality of water sections having cooperating laterally extending flanges upon the upper portions thereof, said cooperating flanges being cut away to provide openings through which the products of combustion may pass, a member supported by the flanges of said sections and having an opening therein, and means associated with said member 120

adjacent said opening and extending rearwardly to adjacent the forward edges of the rear flanges of said sections whereby back drafts from the chimney are diverted away from the combustion chamber of said boiler.

5 4. In a boiler of the character described, a plurality of water sections having laterally extending cooperating flanges at the upper portions thereof and extending forwardly at an incline, said cooperating flanges being cut away to provide openings through which the products of combustion may pass, a member supported by said boiler sections and having an opening through which products of combustion may pass, and a baffle associated with said member adjacent the forward portion of said opening, said baffle extending rearwardly at an angle and substantially overlapping the forward edges of said flanges and adjacent the rear portions of said openings.

10 In testimony whereof, I hereunto affix my signature.
